UNITED STATES PATENT OFFICE

HERBERT E. COOLEY, OF WEST BEND, WISCONSIN

CONTAINER

Application filed December 17, 1926. Serial No. 155,354.

This invention relates to a container especially designed and adapted for use in storing, stacking and shipping cheese, particularly American cheese.

5 The most satisfactory container for cheese heretofore proposed is a nailed wood box which is becoming increasingly costly, which is undesirably heavy and which is difficult to open. While fiber cartons are comparatively 10 inexpensive and easily opened, they are entirely unsuited to cheese because they do not possess the necessary rigidity and strength and because they soften and break down when subjected to moisture or when attacked 15 by the grease or butterfat and paraffin finding their way to the carton from the cheese. The most prolific source of moisture attacking a fiber carton containing cheese is the moisture or sweat of condensation resulting 20 from temperature changes following refrigeration.

One of the principal objects of the present invention is to provide a container for cheese having all of the advantages of a wood box 25 and all of the advantages of a fiber carton and none of the disadvantages of either.

Another important object of the invention is to provide a light weight, comparatively inexpensive container for cheese which holds 30 up notwithstanding the action of moisture and grease or butter-fat and paraffin, which is easily opened and which possesses ample strength, rigidity and insulating properties to protect the cheese at all times.

35 Other objects and advantages reside in certain novel features of the construction, arrangement and combination of parts, reference being had to the accompanying drawing forming a part of this specification and 40 in which:

Figure 1 is a group view in perspective showing a container embodying the present invention and illustrating the parts thereof pulled out and prior to assembly;

45 Figure 2 is a view in vertical section on line 2—2 of Figure 3;

Figure 3 is a view in horizontal section on line 3—3 of Figure 2.

Referring to the drawing wherein for the 50 sake of illustration is shown one embodiment

of the invention, it will be seen that the container comprises an outer fiber carton designated generally at 1 and comprising a tubular body portion 2 which may be rectangular in cross section. The walls of the tubular body portion 2 have integral flaps 3 at their upper end and similar flaps 4 at their lower end. This carton 1 is thus in all respects like the ordinary paper, cardboard or fiber carton.

An inner insulating, protective and reinforcing liner 5 is provided and preferably is constructed of a single piece of thin sheet-like wood, in order to not only reinforce and strengthen the container but also make it resistant to and non-softening under the action of moisture or the action of grease or butterfat or paraffin. While having these advantages the liner 5 is of light weight and the aggregate weight of the liner and the carton is less than that of the ordinary nailed wood box. The body portion of the liner 5 is folded or bent to provide a wall for each wall of the body portion of the carton and in the present embodiment of the invention the liner has four walls which are a part of a single continuous piece of wood. This construction is obtained by cutting a single piece of wood along lines 6 which correspond to the corners of the body portion of the carton, and then folding or bending the single piece 50 of wood about the lines of cut 6. Each cut 6 does not extend entirely through the material of the liner but leaves a skin or thickness of wood sufficient to provide a sort of a hinge connection between adjacent walls. As shown in Figures 2 and 3 the walls of the liner 5 snugly engage the walls of the body portion of the carton and the edges of the ends of the piece of wood making up the liner 5 abut as indicated in 7 in Figure 3, whereby to provide the 55 positive structure of the liner in strengthening and reinforcing relation to the body portion of the carton. The flaps 4 in the lower end of the carton are held in closed position by tacking, riveting or otherwise suitably securing these flaps 4 to a lower end plate 8 of thin sheet-like wood. In the drawing tacks 9 are employed for this purpose. As shown in Figure 2 the lower end of the body of 5 of the liner rests on the margin of the lower end 60

plate 8. The upper end of the body 5 of the liner is engaged by the margin of an upper end plate 10, also constructed of thin sheet-like wood. The flaps 3 bear down on this end plate 10 and are held in such position by strip 11 of adhesive tape or other suitable fastening means.

With this construction the entire inner surface of the carton is lined by thin sheet-like wood which effectively resists the attack of grease or butterfat or paraffin. These substances never reach the fiber carton but are arrested by the wood liner. The wood liner stands up even when subjected to the action of the grease or butterfat or paraffin, although the fiber of the carton would soften and break down were it subjected to the action of these substances. The wood lining likewise stands up when subjected to the action of moisture and the structural integrity of the container is maintained notwithstanding the action of moisture thereon. It is to be understood that containers of this character are particularly liable to be subjected to the action of moisture as after cold storage or other refrigeration to which stored cheese is usually subjected a moisture or sweat of condensation accumulates on the container as incident to the temperature changes which is involved in the removal of the container of cheese from cold storage.

The container is light in weight and is far less costly than the ordinary nailed wood boxes.

36 Another important advantage resides in the fact that the container may be easily opened with the hand or an ordinary knife since it is designed to be closed and sealed by a strip of ordinary adhesive tape or the like.

40 The invention claimed is:

1. A container for cheese comprising an outer fiber carton having a body portion and end flaps, and a liner constructed entirely of thin sheet-like wood and comprising a body portion snugly fitted in the body portion of the carton, an end plate permanently fastened to the flaps at one end of the carton and engaged by the adjacent end of the body portion of the liner, and an end plate engaging the other end of the body portion of the liner and held in position by the adjacent flaps when such flaps are secured in closed position.

2. A container for cheese comprising an outer fiber carton having a body portion made up of angularly disposed walls and end flaps carried by said walls, a single piece liner of thin sheet-like wood folded to provide connected angularly disposed sections fitted flush against the walls of the body portion of the container, a bottom plate of thin sheet-like wood secured to the end flaps at the bottom of the carton, the lower end of the liner resting on the bottom plate, and a top plate of thin sheet-like wood engaged with the upper end

of the liner and held in position by the end flaps at the upper end of the carton.

In witness whereof, I hereto affix my signature.

HERBERT E. COOLEY.
